UNITED STATES PATENT OFFICE

CHARLES ROYAL BOLAND, OF BALTIMORE, MARYLAND

MILK-BOTTLE-CAP REMOVER AND REINSERTER

Application filed October 14, 1929. Serial No. 399,540.

The invention aims to provide an exceptionally simple and inexpensive, yet an unusually efficient and desirable device for removing milk bottle caps and re-inserting them as many times as may be desired, the construction being such that a tight seal is established between the device and the cap instead of leaving part of the opening formed by said device exposed, as in a number of 10 somewhat similar contrivances heretofore produced. The construction is also of such nature that the cap and the device are so tightly connected with each other that there is no lost-motion between them, regardless 15 of repeated use of said device in removing and re-inserting the cap.

With the foregoing in view, the invention resides in the novel subject matter herein-after described and claimed, description being accomplished by reference to the accompanying drawing.

Fig. 1 is a vertical sectional view partly in elevation showing the improved device engaged with a milk bottle cap.

Fig. 2 is an upper end elevation of the device.

Fig. 3 is a vertical sectional view as indicated by line 3—3 of Fig. 2.

The drawing above briefly described illustrates one form of construction and while such construction will be herein specifically explained, it is to be understood that within the scope of the invention as claimed, minor variations may be made.

The numeral 4 denotes a straight vertically elongated shank, 5 has reference to a disk of less diameter than a milk bottle cap and forming a shoulder at the upper end of the shank 4, and 6 denotes an appropriate operating handle, the shank 4, disk or shoulder 5 and the handle 6 being all unitarily united and preferably relatively secured, either by formation of the device from one piece of material or by soldering, brazing or otherwise securing separate pieces together, as may be most desirable. In the construction shown, the handle 6 is integral with the upper end of the shank 4 and the latter passes 50 through a central opening 7 in the disk 5, the

shank and handle being soldered to said disk as indicated at 8.

The upper portion of the shank 4 is provided with a coarse screw thread 9 and below this thread, the shank is smooth as denoted 55 at 10 and is tapered to a sharp penetration point 11. The shank portion 10—11 is by preference in the form of a very acute cone.

In using the device to remove a milk bottle cap, the penetration point 11 is rested 60 upon the central portion of the cap and the entire device is given a downward thrust to the limit allowed by the disk or shoulder 5. In thus forcing the shank 4 through the cap C, the tapered lower end 10 of said shank 65 outwardly crowds the displaced material D and hence places said displaced material under tension, with the result that as soon as the smooth portion 10 clears the cap C, said displaced material will snap into tenacious 70 engagement with the coarse thread 9. Hence, by slightly rotating the device by means of the handle 6, the cap C and the disk or shoulder 5 are tightly clamped against each other and a tenacious connection is provided 75 between the device and the cap, allowing removal of the latter without any danger of the device becoming disconnected from it.

The device may remain attached to the cap as long as necessary and used repeatedly as means 80 for conveniently reinserting the cap and removing it whenever required. Not only is a tight operating connection established between the device and the cap C, but the opening formed by the shank 4 in the cap, is 85 tightly sealed by said shank and there is no loose movement between the cap and the removing and re-inserting device. While the connection and seal are somewhat more effective if the threaded portion of the shank 90 4 be tapered as shown, this may not in all instances be necessary.

When the use of the device in connection with one cap is no longer required, a few 95 turns of one with respect to the other, will so loosen the connection between cap and thread that the shank may be readily pulled out of the opening, being then in readiness for further use with another cap. Due to the difference in diameter between the cap 100

C and the disk 5, it is not essential that the exact center of the former be located, through which to force the shank 4, and the connection and seal between the device and the cap will be just as effective whether the shank 4 be forced through the exact center of the cap or through said cap at an eccentric point.

It will be seen from the foregoing that a device has been provided which may be easily and inexpensively manufactured and sold at small cost, yet that it will be unusually efficient and desirable for removing milk bottle caps and reinserting them to act as closures for bottles which have only been partially emptied. The exact construction disclosed may be followed if desired, but within the scope of the invention as claimed, minor variations may be made as above stated.

I claim:—

20. A milk bottle cap removing and re-inserting device comprising a disk to lie upon the cap, a straight shank projecting downwardly from the central portion of said disk, and a handle fixed with respect to the disk and shank, said shank having its upper portion provided with a coarse screw thread and having its lower portion smooth and downwardly tapered to a sharp penetration point, downward thrusting of said shank through the 25 cap causing said tapered end thereof to outwardly crowd the displaced material, thereby placing said displaced material under tension and causing it to snap inwardly into tenacious engagement with said coarse screw 30 thread, whereby slight rotation of the device by means of the handle will cause said screw thread to tightly clamp the cap and disk together, allowing said cap to be repeatedly removed and inserted by means of 35 the device without breaking the connection 40 between said cap and device.

In testimony whereof I have hereunto affixed my signature.

CHARLES ROYAL BOLAND.
